UNITED STATES PATENT OFFICE.

WILTON F. JENKINS, OF RICHMOND, VIRGINIA.

TROLLEY-HOLDER.

SPECIFICATION forming part of Letters Patent No. 416,920, dated December 10, 1889.

Application filed January 28, 1889. Serial No. 297,798. (No model.)

To all whom it may concern:

Be it known that I, WILTON F. JENKINS, a citizen of the United States, and a resident of Richmond, in the county of Henrico and State 5 of Virginia, have invented certain new and useful Improvements in Trolley-Holders; and I do declare the following to be a full, clear, and exact description of the invention, such as will enable others skilled in the art to which 10 it appertains to make and use the same, reference being had to the accompanying drawings, and to letters of reference marked thereon, which form a part of this specification.

15 Figure 1 of the drawings is a representation of a side view of the trolley-holder. Fig. 2 is a front view of the same.

This invention has relation to holders or standards for trolleys, being especially designed to afford accommodating support to 20 trolleys used in connection with tramway-cars to engage the electrical cables above said cars, all as hereinafter set forth.

The object of the invention is to provide a 25 support which, while sufficiently firm to insure engagement with the cable, is nevertheless of yielding character and designed to give readily either in the lateral direction or in the direction of the length of the cable, so as to 30 avoid injury of the trolley or holder or casual disengagement from the cable.

In the accompanying drawings, the letter A designates the main staff or stem, which is securely fastened to the top of the car, being 35 usually braced by means of guys B or other common bracing devices.

C is a laterally-swinging frame, which is pivoted to the upper end of the stem A by the pivot D. This frame extends upward and 40 downward from the pivotal point, and its upward extension E has arms F, which are designed to support the trolley-hanger G, which

is transversely pivoted to such extension at the point H, so as to swing forward or backward, according to the direction in which the 45 car is running. The lower extension K of the frame C is provided with a slot-guide L, which plays on the lower part of the stem A and allows a small lateral movement of the frame C in either direction. 50

The trolley-hanger G extends above and below the pivot H, and carries pivoted to its arms the trolley N, which is held upward by weighting the lower end of the hanger, as at W, so that a sufficient tension is provided to 55 insure engagement with the cable.

It will be apparent that the trolley pivoted to the hanger G can move readily either forward or backward or laterally to accommodate itself to the position of the cable, which 60 may not be precisely central. So, also, the hanger can readily yield to the swing of the cable between its bearings, and it readily accommodates itself to the lateral motions of the car caused by uneven track, inequality of 65 loading, or to any swerving in passing around curves. The hanger, it will be observed, adjusts itself automatically when the direction of motion of the car is changed.

Having described this invention, what I 70 claim, and desire to secure by Letters Patent, is—

In a trolley-holder, the combination, with a laterally-yielding support having a slotted guide at its lower end, of a main stem to 75 which said support is pivoted and a weighted trolley-hanger pivoted at the upper end of said support, substantially as specified.

In testimony whereof I affix my signature in presence of two witnesses.

WILTON F. JENKINS.
